(57) **CLAIM**

The ornamental design for a hooded jacket, as shown and described.

DESCRIPTION

FIG. 1 is a front elevational view of a hooded jacket showing my new design;

FIG. 2 is a left side elevational view thereof;

FIG. 3 is a right side elevational view thereof;

FIG. 4 is a rear elevational view thereof; and,

FIG. 5 is a top plan view thereof.

Wherein the broken lines are boundaries that form no part of the design to be patented.
